ATTORNEY.

UNITED STATES PATENT OFFICE.

FRANK H. WHITE, OF GWYNEDD, PENNSYLVANIA.

GARMENT-SUPPORTER.

1,197,699.

Specification of Letters Patent. Patented Sept. 12, 1916.

Application filed September 27, 1915. Serial No. 52,794.

To all whom it may concern:

Be it known that I, FRANK H. WHITE, a citizen of the United States, residing at Gwynedd, county of Montgomery, and State 5 of Pennsylvania, have invented a new and useful Improvement in Garment-Supporters, of which the following is a full, clear, and exact description, reference being had to the accompanying drawings, which form a part 10 of this specification.

The object of my invention is to provide a garment support upon which a coat or other garment may be draped and which, together with the garment draped thereon, 15 may be placed in a suit case and removed therefrom and suspended upon a hook or nail and which, when thus suspended, may also be utilized for the purpose of supporting trousers.

20 The invention is an improvement upon the reinforcing and shape-keeping card for clothes set forth in Patent No. 1,021,593, dated March 26, 1912, issued to Solomon D. Gilkerson.

25 A preferred embodiment of the invention is shown in the drawings, in which—

Figure 1 is a front view of the form. Fig. 2 is a view of the two parts of a shoulder piece in process of manufacture. Fig. 30 3 is a cross section through the shoulder part of the form. Fig. 4 is a cross-sectional view of the form, showing its adaptation to use in a suit case.

The form comprises a plate *a* of cardboard 35 or other material, having a relatively narrow top edge to which is hinged a flap *b* having a hole reinforced by a gromet *c*. From the flap *b* the edges of the plate slope downwardly in an inclined direction and, 40 thence slope downwardly in a substantially vertical direction, forming the shoulder portions of the form.

In Fig. 2 are shown two pieces of cardboard, which, by means of suitable dies, are 45 formed with raised strips *d* and *e* shaped, in the direction of their longitudinal direction, to conform to the shoulder portion of the plate *a*. These raised strips are then cut out, forming two strips, curved in a 50 lateral direction, and adapted to be applied, as shown in Fig. 3, to the edge of the shoulder portion of the form. The abutting outer longitudinal edges of the strips *d* and *e*

are secured together by means of an overlapping piece *f* glued to both strips. The 55 entire form is then covered with fabric *g*, which holds the shoulder pieces in position and imparts a finish to the article.

The lower edge of the form is straight and above the lower edge the form is provided 60 with a slot *h*.

In use the coat is draped over the form and is then folded over the lower edge, the lower half of the coat being placed against the form and the whole inserted, in an inverted position, in a suit case, as shown in Fig. 4, the flap *b* adapting itself to the bottom of the case.

When the form is removed from the case, 70 it is turned right side up and may be suspended from the flap *b* without removing or disturbing the coat. A pair of trousers may be slipped through the slot *h* and also suspended from the form.

Having now fully described my invention, 75 what I claim and desire to protect by Letters Patent is:

1. A garment supporter and shaper comprising a flat plate having edges shaped to form shoulder portions, a pair of complementary strips shaped, in the direction of their longitudinal extensions, to conform to said edges, said strips being curved in a lateral direction and applied to opposite sides of the plate along said edges to form 85 raised shoulder pieces.

2. A garment supporter and shaper comprising a flat plate having edges shaped to form shoulder portions, a pair of complementary strips shaped, in the direction of 90 their longitudinal extensions, to conform to said edges, said strips being curved in a lateral direction and applied to opposite sides of the plate along said edges to form raised shoulder pieces, the outer edges of 95 said raised strips extending beyond the edge of the plate and abutting together, and a piece overlapping and secured to both raised strips.

In testimony of which invention, I have 100 hereunto set my hand, at Philadelphia, Penna., on this 22nd day of September, 1915.

FRANK H. WHITE.
